(57) **CLAIM**

The ornamental design for a disk loading device for disk player, as shown and described.

DESCRIPTION

FIG. 1 is a front elevational view of a disk loading device for disk player showing my new design;

FIG. 2 is a rear elevational view thereof;

FIG. 3 is a left side elevational view thereof;

FIG. 4 is a right side elevational view thereof;

FIG. 5 is a top plan elevational view thereof; and,

FIG. 6 is a bottom plan elevational view thereof.
